UNITED STATES PATENT OFFICE.

JAMES H. WARING, OF MILWAUKEE, WISCONSIN, ASSIGNOR OF ONE-HALF TO PAUL F. SCHRYER, OF WAUWATOSA, WISCONSIN.

PENCIL.

REISSUED

Application filed February 28, 1921. Serial No. 448,318.

To all whom it may concern:

Be it known that I, JAMES H. WARING, a citizen of the United States, and resident of Milwaukee, in the county of Milwaukee and State of Wisconsin, have invented certain new and useful Improvements in Pencils; and I do hereby declare that the following is a full, clear, and exact description thereof.

10 My invention relates to improvements in pencils, and more particularly to that type adapted to be refilled.

15 The invention has for its object to provide a pencil of this type which is durable, efficient and positive in operation.

A more specific object resides in the arrangement of lead feeding and holding means, whereby the lead is firmly engaged and projected from the pencil and positively 20 held in its projected position to the extent that retraction of the lead is impossible, without damage thereto.

Another object lies in the provision of 25 encased operating means whereby the lead is prevented from being accidentally projected from the pencil.

A still further object is to provide a pencil of this type with ball friction clutches for engaging the lead whereby a positive grip 30 can be obtained and at the same time prevent damage to the lead.

With these and other objects in view which will be apparent as the description proceeds, my invention consists in what is 35 hereinafter more particularly defined and pointed out in the appended claims.

In the drawings:

Figure 1 is an elevational view of the invention, with parts broken away and in 40 section to more clearly illustrate the novel points of construction, and

Figure 2 is a transverse sectional view through the lead projecting clutch, taken on the line 2-2 of Figure 1.

45 Referring now more particularly to the accompanying drawing, the numeral 1 designates an outer casing provided with a tapered end 2 having fitted therein by any suitable method, a lead guide 3, provided 50 with a central recess to permit the lead L to pass therethrough. Disposed within the casing 1 adjacent its tapered end 2 is a clutch housing 4, provided with inwardly

turned flanges 5 adapted to retain a pair of ball clutches C and C' which respectively 55 project and hold the lead against retraction.

The clutch C comprises an annular ring 6 slidable within the housing 4 and provided with a tapered ball engaging surface, and a central opening 7 which permits the 60 ring to be mounted upon the end of a lead housing 8. Surrounding the lead and disposed within the annular ring 6, are a plurality of gripping balls B, which are retained in their place by a ball retainer 9. 65

The clutch C' which opposes the clutch C to prevent retraction of the lead, is similarly constructed and disposed between its annular ring and the ball retainer 9 of clutch C, is a spring 10 adapted to render both 70 clutches operative, and having an additional function of returning the clutch C to its normal position after the lead has been projected. The ball retainer 9 of the clutch C' is provided with a recess 9' to receive 75 the lead guide 3.

The open end of the casing 1 is provided with a collar 11, having a central orifice to permit the lead housing 8 to extend therethrough. Fitted over the end of the casing 80 and abutting the annular flange 1' is a sleeve 12 provided with an enlarged end 13, which end is turned inwardly to provide a retaining bead 14. Confined within the enlarged end 13 is a cap 15 adapted to engage and 85 operate the lead housing 8, the cap having its movement limited in one direction by the bead 14 and in the opposite direction by the shoulder 16 formed between the sleeve and the enlarged end 13. 90

From the foregoing it will be seen that as the cap is depressed, the clutch C mounted on the end of the housing 8, will grip and project the lead from the guide 3. Upon releasing the cap the spring 10 will cause the 95 clutch C to be returned to its normal position, and at the same time will render the clutch C' operative upon any tendency of the lead to be retracted by the clutch C upon its return movement. It will further 100 be noted that when the clutch C is in its normal position, the clutch C' will cooperate with it to assist in preventing the lead from being pushed back when pencil is in use.

While I have shown and described one 105 specific method of carrying out my present

invention it will be understood that various changes in minor details of construction are contemplated as within the appended claims.

I claim:

- 5 1. In a pencil, a casing, means movable within the casing for projecting the lead, a sleeve fitted upon one end of the casing and provided with an enlarged end, and a cap movable within the enlarged end of the
10 sleeve and limited by said sleeve so as not to move beyond the end of said sleeve, said cap being operable for actuating said lead projecting means.
- 15 2. In a device of the class described, the combination of lead, a lead housing, a ring rigid therewith and having ball engaging

surfaces, a group of balls, a ball retainer, a second ring, a second group of balls, said ring having ball engaging surfaces, a spring contacting with said second ring and said retainer, a second ball retainer, a lead guide rigid therewith, a housing for said spring, said rings, said balls, and said retainers limiting the movement of said first mentioned ring, and a casing enveloping said lead housing, said second mentioned housing and said lead guide.

In testimony that I claim the foregoing I have hereunto set my hand at Milwaukee, in the county of Milwaukee and State of Wisconsin.

JAMES H. WARING.
